UNITED STATES PATENT OFFICE.

JOHN P. CARLSON, OF BROOKLYN, NEW YORK.

EXPLOSIVE-ENGINE.

1,220,951.

Specification of Letters Patent. Patented Mar. 27, 1917.

Application filed August 17, 1915. Serial No. 45,989.

To all whom it may concern:

Be it known that I, JOHN P. CARLSON, a citizen of the United States, residing at Brooklyn, in the county of Kings and State of New York, have invented certain new and useful improvements in Explosive-Engines, of which the following is a specification.

This invention relates to explosive engines of the type shown in a patent to 10 David Duffy, No. 1,142,316, issued June 8, 1915, and owned by me.

The object of the present invention is to provide a novel and improved construction and arrangement of the parts whereby the 15 operation of the engine will be simplified and the cost of production reduced, while the efficiency of the engine will be enhanced.

The invention is illustrated in the accompanying drawings, in which:

20 Fig. 1 is an elevation of a four-cycle engine with parts broken away, embodying my present improvements;

Fig. 2 is a vertical section of one of the 25 cylinders with a portion of the valve or rotary sleeve removed, the piston being omitted;

Fig. 3 is a horizontal section on the line 3-3 of Fig. 2;

Fig. 4 is a horizontal section on the line 30 4-4 of Fig. 2;

Figs. 5, 6, 7 and 8 are diagrammatic sectional views, showing the position of the rotary sleeve and the relative position of the ports in the cylinder during each stroke 35 of the piston;

Fig. 9 is a detail vertical section.

In carrying out my invention, I employ any desired number of cylinders, indicated at 1, which are secured upon the crank case 40 2. Within each cylinder is a rotating sleeve or valve 3 and this valve or sleeve incloses the piston 3^a and constitutes a pressure cylinder. A worm gear 4 is secured upon the crank shaft 5 near one end of the crank case and this worm gear meshes with a worm pinion 6 on the lower end of a vertically disposed shaft 7 which is equipped at its upper end with a pinion 8 meshing with a gear 9 on the lower end of the adjacent sleeve 3. The gear 9 meshes with a similar gear 10 on the lower end of the sleeve in the adjacent cylinder and the said gear 10 in turn meshes with a similar gear on the sleeve in the next cylinder so that the sleeves 55 in all the cylinders will be positively rotated through a train of gearing which extends

longitudinally of the crank case. Between the under side of each of said gears and the top of the crank case, I interpose a friction ring 11 which fits in an annular groove in 60 the under side of the gear and is secured upon the crank case. The ring is packed in lubricant so that the sleeve may rotate about its vertical axis freely and the frictional wear between the parts is reduced. The 65 lower end of the cylinder is offset so as to project over the gear and thereby prevent longitudinal displacement of the sleeve or valve.

The cylinders are each provided with a 70 water jacket and a head 13 is secured upon the cylinders and fits into the upper ends thereof, the said head being also provided with a water jacket. In the side wall of each cylinder, adjacent the upper end of the 75 same, I provide a plurality of pairs of ports which are so disposed that the web between the ports of each pair will be spaced 120° from the web between the ports of each of the other pairs. The webs are indicated at 80 14 and it will readily understood that one port 15 is intended to serve as an exhaust, while the other port 16 serves as an intake. The several exhaust ports communicate with an upper annular passage 17 formed in the 85 wall of the cylinder and extending entirely around the same, said passage communicating with an exhaust manifold 18 which is mounted in any convenient manner upon the engine and extends across the front of the 90 several cylinders. In like manner, the intake ports communicate with a lower annular passage 19 in the wall of the cylinder, which passage 19 communicates with the intake manifold 20, as will be readily understood. The ports 15 and 16 have their greatest dimension running vertically so that they 95 will extend to the head which fits within the upper end of the cylinder and, consequently, provide for a more perfect intake and 100 distribution of the gas and a more complete exhaust of the burnt gases and consequent scavenging of the cylinder.

The sleeve or valve 3 is provided at its upper end with ports 21 which are spaced 120° 105 apart and which, in the operation of the engine, will register successively with the intake and exhaust ports of the cylinder in which the sleeve is mounted. These ports 21 are of the same dimensions and in the same horizontal plane with the ports 15 and 16 so that a perfect registry or alignment of

the ports will be effected and the intake and exhaust operations facilitated.

It will be readily understood that the sleeves or valves will be continuously rotated and that the several gears or pinions connecting the sleeves with the crank shaft will be so proportioned that the operation of the sleeves will be properly timed to effect the registry of the ports at the desired intervals. By referring to Figs. 5, 6, 7 and 8, it will be noted that on the intake stroke, each of the ports 21 in the sleeve will register with an intake port of the cylinder so that a copious charge of fuel will be admitted to the cylinder and this charge will be evenly distributed within the cylinder. As the crank shaft rotates, the sleeve will, of course, be rotated and the ports will be carried out of alinement with the intake ports of the cylinder and will move to the position shown in Fig. 6 whereupon compression of the charge will begin, all the ports in the cylinder being covered or closed. During the interval required for the travel of the ports 21 from the intake port of one pair of ports to the exhaust port of the next pair of ports, the charge will be compressed and fired, as will be readily understood upon reference to Figs. 6 and 7 and, upon completion of the firing or power stroke, the ports 21 of the sleeve will be brought into registry or alinement with the exhaust ports of the cylinder, as shown in Fig. 8. Inasmuch as all the exhaust ports communicate with the annular passage 19 in the wall of the cylinder, a quick and complete exhaustion will be effected so that upon a slight additional movement of the sleeve, the intake ports of the cylinder will be opened and a second charge may be received.

It will be noted more particularly upon reference to Fig. 2, that the intake ports communicate with the annular passage in the wall of the cylinder by branches which extend upwardly from the annular passage to the lower ends of the ports so that the fuel will be admitted to the cylinder the instant the piston uncovers the upper ends of the ports and, as these ports are arranged close to and preferably directly under the head of the cylinder, it is obvious that a full charge will be admitted and that it is not necessary for the piston to move through a part of its stroke before admitting fuel to the cylinder. The exhaust ports have branches which incline upwardly therefrom to communicate with the upper annular passage in the wall of the cylinder so that the burnt gases will be driven from the cylinder in a natural course of flow to exhaust fully and freely as the piston begins its exhaust stroke.

Having thus described the invention, what is claimed as new is:

65. 1. The combination of a cylinder having

upper and lower annular passages in its wall and having pairs of ports in said wall, all the ports being in the same radial plane of the cylinder and the pairs of ports being spaced equidistantly around the cylinder, 70 one port of each pair being an exhaust port and having its upper and lower walls inclined upwardly and outwardly to communicate with the upper annular passage and the other port of the pair being an intake 75 port and having its upper and lower end walls inclined downwardly and outwardly to communicate with the lower annular passage, whereby fuel drawn into the cylinder will be deflected upwardly, a rotary valve 80 sleeve disposed within the cylinder and held against longitudinal movement therein and provided with ports adapted to register successively with all the ports in the cylinder, a piston reciprocating in the valve 85 sleeve, and means driven by the piston to continuously rotate said sleeve.

2. In internal combustion engine construction, a crank case and cylinder removably connected, the crank case having a top 90 wall formed with an opening communicating with the cylinder and of less diameter and in its upper face with a recess providing a chamber around and below the lower end of the cylinder, the cylinder being formed 95 with inlet and exhaust ports, a removable cylinder head, a sleeve valve forming the explosive chamber proper rotatably mounted in the cylinder and projecting into the chamber formed between the cylinder and casing, 100 said valve being removable through the end of the cylinder when the cylinder head is removed, a gear ring detachably secured about the lower extending end of the sleeve valve, a packing ring carried by the gear 105 ring and engaging the upper wall of the casing to shut off the chamber from communication with the casing and cylinder and thereby provide a lubricant space, a shaft extending through the upper wall of the 110 casing and adapted to be driven by the engine, and a pinion carried by the shaft and meshing with the gear ring to continuously rotate the sleeve valve.

3. In internal combustion engine construction, a cylinder, a crank casing, the cylinder and crank casing providing between them an annular chamber of greater diameter than the internal diameter of the cylinder, the cylinder being formed with inlet and exhaust ports, a cylinder head detachably secured to the cylinder and having a thickened portion projecting within the cylinder with its peripheral edge spaced from the peripheral wall of the cylinder, a sleeve valve 115 rotatably mounted in the cylinder and forming the combustion chamber thereof, the upper end of the sleeve valve projecting between the cylinder wall and the inwardly extending thickened portion of the cylinder 120 125 130

head, a packing ring carried by the thickened portion of the cylinder head and engaging the sleeve valve, a gear ring about the lower end of the sleeve valve and seating in the annular chamber, means releasable from within the valve connecting the valve and gear ring, the sleeve valve being formed with openings adapted to register with the openings of the cylinder, and means driven by the engine for driving the gear ring and its sleeve valve.

4. In internal combustion engine construc-

tion, an engine cylinder having inlet and exhaust ports, a removable cylinder head; a sleeve valve rotatable within the cylinder and having ports to register with the cylinder ports, the sleeve valve forming the combustion chamber of the cylinder and being removable upon removal of the cylinder head, and means coöperating with that end 20 of the sleeve valve opposite the cylinder head for rotating the sleeve valve.

In testimony whereof I affix my signature.

JOHN P. CARLSON. [L.S.]
